(57) CLAIM

The ornamental design for a motorcycle gas tank mailbox, as shown and described.

DESCRIPTION

The design is for the particular and distinctive shape of a motorcycle gas tank primarily for use as a mailbox for the receipt and delivery of mail.

FIG. 1 is a front elevational view of a motorcycle gas tank mailbox showing my new design;

FIG. 2 is a side elevational view thereof, the opposite side is a mirror image;

FIG. 3 is a bottom plan view thereof; and,

FIG. 4 is a front elevational view with the lid in an open position.
